UNITED STATES PATENT OFFICE.

SAMUEL S. MATTHES, OF MANSFIELD, OHIO, ASSIGNOR TO THE OHIO BRASS COMPANY, OF MANSFIELD, OHIO, A CORPORATION OF NEW JERSEY.

REELING DEVICE.

1,366,199.

Specification of Letters Patent. Patented Jan. 18, 1921.

Application filed April 9, 1919. Serial No. 288,784.

To all whom it may concern:

Be it known that I, SAMUEL S. MATTHES, citizen of the United States of America, residing at Mansfield, in the county of Rich- 5 land and State of Ohio, have invented cer- tain new and useful Improvements in Reeling Devices, of which the following is a specification.

My invention relates to improvements in 10 winding devices and has particular reference to the retrieving and resetting mechanism, and I have described its use and operation as applied to trolley retrievers although its use is not limited to trolley re- 15

trievers. One of the objects of my invention is to 20 provide an improved device of this character which will be simple, durable, reliable, and compact in construction, and effective

and efficient in operation. Another object is to provide a reeling device comprising mechanism dependent upon the winding up of the power spring to a 25 predetermined tension for resetting the device to normal operating condition.

A further object is to provide a reeling device comprising mechanism compelling the winding up of the power spring to a predetermined tension when resetting the 30 device.

A still further object is to provide a reeling device comprising a resetting device and mechanism to coöperate therewith and operable by the power spring when wound 35 up to a predetermined tension to permit movement of said device into a position where it operates to prevent further winding up of the spring.

To the attainment of these ends and the 40 accomplishment of other new and useful objects, as will appear, the invention consists in the novel features of the design, combination and arrangement of the several parts to be hereinafter more fully de- 45 scribed, and claimed, and shown in the accompanying drawings which illustrate one embodiment of the invention, and in which:—

Figure 1 is a side view of a winding de- 50 vice embodying my improvements and shown partly in section to illustrate the constructional arrangement of the several parts, as applied to a trolley retriever.

Fig. 2 is a sectional view taken on the 55 line 2—2 of Fig. 1, and showing the power

spring wound up and the setting mechanism in normal operative condition.

Fig. 3 is a sectional view substantially on the line 3—3 of Fig. 1, and showing the retriever disk in interlocked relation with 60 the case and the drum free to rotate in either direction under the action of the trolley pole.

Fig. 4 is a similar view indicating the mechanism in the act of unlocking the retriever disk, (dotted lines) and also showing the retriever disk unlocked from the case and about to commence its retrieving action, (full lines).

Figs. 5 and 6 are views of a portion of the 70 case and the retriever disk and showing the interlocking or setting mechanism in various positions and which will be referred to hereinafter.

Fig. 7 is a view of a portion of the re- 75 triever disk showing the opposite side there- of than that shown in the other views.

The same reference characters indicate the same parts throughout the several 80 views.

In the drawings, 1 designates the case of an ordinary retriever and which comprises, as shown, a cover 2 which may be removably secured thereto in any suitable or well known manner. The case is formed with a 85 recess 3 wherein is mounted a power or retrieving spring 4, which has its outer end secured to the case, as by rivets 5, or otherwise. The inner end of this spring is connected in any well known or suitable manner, preferably as shown in Fig. 2, to the hub extension 6 of a driver 7 which is rotatably mounted on the shaft 8 secured within the case. The driver comprises a power arm 9 which extends and has a limited amount of movement between stops 10 and 11 provided on one side of the retriever member or disk 12 and is constantly urged to rotate in the direction toward, and normally held in engagement with, the stop 10 by the tension of the power spring. Tending 95 to rotate the driver in the opposite direction, as toward and into engagement with the stop 11 is a control spring 13 having one end attached to the arm 9 of the driver 100 and its other end adjustably connected to the retriever disk as by means of a screw 14 passing through a lug 15 formed on the disk and having threaded engagement with the nut 16 secured in the end of the spring. It 105

110

will be apparent that by adjusting the screw 14, the spring 13 may be held under any desired or required amount of tension.

Pivots secured to the arm 9 as at 17 is a movable member 18 which is constantly urged to rotate toward, and adapted when in operative position to be held in engagement with, its co-operating stop 19, (see Figs. 2 and 5) by a spring 20 having one end connected to the movable member at 21 and its other end connected to the arm 9 at 22'. This member 18 is normally held out of engagement with its stop 19 and in the position shown in Figs. 2 and 3, and is constructed and arranged so that when it is in operative position its end extends slightly beyond the end of the arm 9, forming an offset or shoulder 21', (see Fig. 5), the purpose of which will be brought out hereinafter.

The retriever member or disk 12 is mounted for rotation in either direction and is adapted to be rotated in one direction by the power spring 4 through the medium of the driver 7 to wind up the trolley rope and thereby pull down the trolley pole, and it is adapted to be rotated in the opposite direction for the purpose of resetting or winding up said spring. This disk is provided with a flange 22 having a suitable slot in which is arranged a double latch which is adapted to normally lock the retriever disk to the case so as to prevent its rotation and to hold the power spring under tension. This latch comprises two levers 23 and 24 which are pivoted at 25 and 26 respectively. The inner or adjacent ends of the levers are knuckle jointed so that they will both move simultaneously, the lever 23 at this end being notched while the corresponding end of the lever 24 is formed to operate in said notch as shown in Figs. 3 to 7 inclusive. When the latch is in locking position the free ends 27 and 28 respectively will be projected or thrown beyond the periphery of the flange 22 on the retriever disk and in position to engage the fixed lugs 29 and 30 which are preferably formed integrally on the inner wall of the case. For convenience of description I will hereinafter refer to the end 27 of the latch as the "lock" end, and the end 28 as the "stop" end. Thus it will be seen that when the latch is thrown out and the "lock" end is in engagement with the "stop" lug 29, the retriever disk will be positively locked against rotation by the spring 3 and in a direction to wind up the trolley rope. The operation of the "stop" end of the latch will be described later. The two levers which comprise this latch, as is seen, are formed so that when said levers are in inward or released position, as shown in Figs. 5, 6 and 7, no portion of them will project in the path of the lugs 29 and 30, thus leaving the disk free to rotate. A coil spring 31 having one end connected to the lever 24 and its other

end connected to the retriever disk operates to maintain the latch in locking or outward position.

Rotatably mounted, preferably upon another hub extension 32 of the retriever disk 70 is a drum 33 adapted to receive the trolley rope 34. This drum is formed with a compartment 35 wherein is mounted a service spring 36, which operates to rotate the drum in the direction to keep the trolley rope taut. 75 The outer end of this spring is connected to the drum in any suitable or desirable manner while its inner end may be connected to a stationary sleeve 37, which may be mounted for adjustment by means of ratchet teeth, so not shown, or otherwise.

The drum normally follows the movement of the trolley pole as the trolley pole and drum are connected by a rope, and in case of an abnormal rapid rise in said pole mechanism is actuated which will unlock the retriever disk and connect it with the drum so that the drum will be rotated in the direction to wind up the trolley rope and pull down the pole. In order to throw in the 90 latch and release the retriever disk the drum carries a plurality of centrifugal dogs 38, which are pivotally mounted in suitable sockets or bearings 39, formed in integral bosses 40 on the side of the drum adjacent 95 the retriever disk. When normally operating, these dogs are yieldably maintained in inward or retracted position by springs 41, the free ends of the dogs resting against the adjacent bosses, as shown in Fig. 3. These 100 dogs are arranged so that they will be sensitive to abnormal rapid fluctuations of the trolley pole, such for instance as when the pole leaves the wire and flies upwardly. Because of the undue speed of the drum incident to the quick upward movement of the pole the dogs will move outwardly against the peripheral flange 22, on the retriever disk under the action of centrifugal force. 105

It will be noticed that the knuckle joint 110 of the latch, when the latch is in locking position, lies within the flange 22 and hence within the path of the free ends of the tripping or centrifugal dogs 38. In consequence, the tripping dog, which at the instant is the nearest to the knuckle joint of the latch, will strike said joint and force it outwardly, thus throwing the "lock" and "stop" ends of the latch inwardly and release the retriever disk. In order to insure 115 a positive releasing action on the part of the dogs, I provide an outstanding rib 42 on the face of the retriever disk adjacent the centrifugal dogs. This rib is positioned adjacent the knuckle joint of the latch to provide 120 a comparatively narrow space between the rib and the flange 22. In addition the free ends of the tripping dogs are provided with extensions 43 of sufficient thickness to pass 125 through the channel or space between the 130

rib and flange and thereby positively force the knuckle joint of the latch outwardly. For the purpose of maintaining the latch in inward or released position during the rotation of the disk by the power spring and during the resetting or winding up operation of the device to normal operative condition, I provide the lever 23 with an outstanding pin 45, which is normally disposed 5 in the position shown in Fig. 3 and where it operates to maintain the movable member 18 in inoperative position and out of engagement with its co-operating stop 19. By movement of the latch into inward or 10 released position, this pin is carried out of the path of the movable member 18 which will then move into engagement with the stop 19 as shown in Fig. 5. In this position of the movable member 18 it will be noted 15 that it forms an obstruction in the path of the pin 45 and thus positively prevents movement of the latch into outward or operative position prior to the unwinding of the power spring and the resetting or 20 rewinding of said spring to a predetermined tension, as will be more clearly described 25 hereinafter.

Assuming now that the latch has been thrown out and the retriever disk released, 30 as indicated in Fig. 4, it now remains to lock the retriever disk and drum together so that the retriever disk will rotate the drum in the direction to wind up the trolley rope and pull down the pole. This is accomplished by the tripping dog which, after 35 actuating the knuckle-joint, passes the latch and continues until it reaches the shoulder 46 formed in the flange 22 of the retriever disk. By thus engaging said shoulder the 40 tripping dog positively interlocks the retriever disk and drum and the latter will thereby be carried with the retriever disk and will wind up the trolley rope.

In order that a clear understanding of my 45 invention may be had, a brief statement of the operation is as follows. When the power spring is wound up or set and the parts are in their normal position they will be as represented in Figs. 1, 2 and 3. The latch 50 will be in outward position and the "lock" end 27 of the lever 23 held in engagement with the "lock" lug 29 of the case and the movable member 18 held in inoperative position by the pin 45. The arm 9 of the driver 55 7 is held in engagement with the stop 10 by the tension of the power spring 4 and against the action of the control spring 13, and the centrifugal dogs 38 held in engagement with the bosses 40 as shown. In this 60 relation of the parts the drum is free to be rotated in a direction to wind up the trolley rope by action of the service spring 36 which is of sufficient tension to keep the rope taut at all times during the rise and fall of the 65 trolley pole during operation. When the

rope is rapidly unwound from the drum as when the trolley rope jumps the wire, the sudden impulse or rapid rotation of the drum will cause the dogs 38 to move outwardly by centrifugal force and actuate the 70 latch to release the retriever disk and then interlock the drum with the disk in the manner hereinbefore described. When this has taken place the relation of the parts will be as represented in Figs. 4 and 5. Next 75 the retriever disk and the drum, under the influence of the power spring 4, will be caused to rotate in a rope winding direction and wind up the rope and thereby pull down the trolley pole. As the drum rotates, the power spring, which is normally held under tension slightly higher than that of the control spring 13, weakens whereupon the arm 9 of the driver will be positioned against the stop 11 by action of the control spring 13. This positioning of the arm 9 as is seen 80 in Fig. 6, carries the movable member 18 out of the path of or alignment with the pin 45 which holds the latch in released position and which is then brought to bear or rest against the end of the arm 9. The parts will remain in this relation during the unwinding 85 of the power spring and the consequent winding up of the trolley rope.

To set or restore the parts to their normal operative condition after the device has operated as above, it is only necessary to pull out on the trolley rope thereby unwinding the same and rotating the drum and the retriever disk in the direction indicated by arrows in 90 Figs. 5 and 6. While the rope is being pulled out and the drum and retriever disk revolve, winding up the power spring, the arm 9 of the driver is held in engagement with the stop 11 by the action of control spring 13 and the latch held in released position by engagement of its pin 45 with the end of the arm 9 until the power spring is wound up to a 95 point where its tension becomes equal to or balances the tension of the control spring 18. Then upon continued rotation of the parts in the same direction and the consequent further tensioning of the power spring, the arm 9 under the influence of this increased tension will move toward and into 100 engagement with the stop 10 and against the action of the control spring. During this positioning of the arm 9, it will move out of alignment or engagement with the pin 45, and the movable member 18 will be brought 105 into engagement with said pin at 21' and shifted to normal inoperative position, thus leaving the path of the pin 45 unobstructed whereupon the latch under the influence of 110 its spring 31, will immediately move into outward or operative position as shown in Fig. 2. If at this instant the latch is not positioned between the stop lugs 29 and 30 115 it will in the continued rotation of the disk ride over the surface 43 and the "lock" end 120 125 130

of the latch will snap in behind the lock lug 29 in position to prevent or lock the retriever disk against rotation in the retrieving direction as above described. This snapping in of the latch does not indicate to the conductor that the latch is in locking position and the operator continues pulling out on the rope until the "stop" end 28 of the latch strikes the "stop" lug 30 of the casing. 10 This action positively prevents the further winding up of the spring and indicates to the operator that the latch is in locking position. As soon then as the pull on the trolley rope is released, the disk will move in the reverse direction until the "lock" end 27 of 15 the latch is brought into engagement with the "lock" lug 29 of the casing and locks the disk against rotation until it is again released by the centrifugal dogs 38. It now 20 remains to unlock the drum from the retriever disk, which it will be remembered were held interlocked while the parts were being restored to normal operative condition. This is accomplished as soon as the 25 pull on the trolley pole is released, whereupon the drum will start to rotate in the opposite direction by the action of the service spring 36, and in so doing it carries the centrifugal dog 38 out of engagement with the 30 stop shoulder 42 of the disk. The dog moves out until it passes the end of the guide rib 46 and it is then drawn inwardly against the boss 40 by its spring 41, thus finally unlocking the drum from the disk and leaving the 35 drum free to again normally wind up and unwind the trolley rope.

It will be evident from the foregoing that the mechanism which operates to automatically restore the latch to locking position is 40 controlled by the tension of the control spring 13 and that by varying this tension, as herein provided, the device may be adjusted to obtain any desired or required amount of retrieving action.

Having thus fully described my invention and illustrated one embodiment of the same, I do not wish to be limited to the details of 45 the construction shown since these can obviously be changed without departing from the spirit and scope of the invention.

I claim:

1. In a trolley retriever the combination of a case provided with a stop, a rotatable retriever disk therein, a spring for rotating the disk in one direction and normally held under tension; a locking device carried by the disk and movable into engagement with the stop for holding the disk against rotation by the spring; and mechanism connecting the spring and the disk and operable by the spring when wound up to a predetermined tension for effecting the movement of said locking device into locking position. 55

2. In a trolley retriever the combination 60 of a case provided with a stop, a retriever

disk mounted therein for rotation, a spring for rotating the disk in one direction, a locking device carried by the disk and normally having engagement with the stop for holding the disk against rotation by the 70 spring, means for moving the locking device out of engagement with the stop to permit rotation of the disk by the spring, and mechanism connecting the spring and the disk and embodying an element adapted to 75 coöperate with the locking device for maintaining said device in inoperative position during rotation of the disk.

3. In a trolley retriever the combination of a case provided with a stop, a rotatable retriever disk therein, a spring for rotating the disk in one direction, a locking device carried by the disk and movable into and out of engagement with the stop to normally lock the disk against rotation by the 80 spring, and mechanism connecting the spring and the disk for controlling the movement of said locking device into locking position and whereby the power of the 85 spring is transmitted to the disk, said mechanism comprising an element having engagement with the spring and normally held in one position relative to said disk by the action of said spring, and another spring 90 engaging the disk and element and operating to move said element to another position when the tension of the first mentioned 95 spring is relaxed.

4. In a trolley retriever the combination of a case, a retriever disk mounted therein for rotation, a spring constantly tending to rotate the disk in one direction, a lock carried by the retriever disk, means under the control of the spring and operable upon a predetermined tensioning of the spring for 100 permitting movement of the lock into locking position, and stops for engagement with the lock to restrain the rotation of the disk in either direction. 105

5. The combination of a rotatable retriever disk, a power spring constantly urging said disk in one direction of rotation, means for rotating the disk in the reverse direction and against the tension of the power spring, a locking device carried by 110 the disk and operable when set to lock the disk against rotation in either direction, means for coacting with the device when set to hold the disk against rotation, means tending to constantly urge the locking device to move into locking position, and means under the control of the power spring for preventing movement of the locking device 115 into locking position prior to the winding up of the spring to a predetermined tension. 120

6. The combination of a retriever disk, a spring constantly urging the disk in one direction of rotation, means for rotating the disk in the reverse direction and against the tension of the spring, a locking device car- 125

ried by the disk for locking the disk against rotation in either direction, means coöperating with the locking device to hold the disk, means for releasing the locking device, a driver having engagement with the spring and normally maintained in yieldable contact with the disk by the action of the spring, and a movable member carried by the driver and normally held in inoperative position by engagement with the lock for holding the lock in released position during rotation of the disk by the spring.

7. The combination of a rotatable retriever disk, a spring for rotating the disk in one direction, means for rotating the disk in the opposite direction and against the action of the spring, a locking device carried by the disk for locking the disk against rotation by the spring, means for coacting 15 with the locking device to hold the disk against rotation, and an element rotatable with the disk and having a limited amount of movement relatively thereto adapted to maintain the lock in released position while 20 the spring is being wound up and dependent upon a predetermined tension of the spring for causing said locking device to move into locking position.

8. The combination of a retriever disk, 30 a power spring constantly urging the disk in one direction of rotation, means for rotating the disk in the reverse direction and against the action of the spring, a locking device carried by the disk for normally locking the disk against rotation in either direction, means coöperating with the locking device to hold the disk, means for releasing the lock, a driver rotatable with the disk and having a limited amount of movement 35 relatively thereto and normally maintained in one position relative to said disk by the action of the spring to which it is connected, a control spring connected to and operating to move the driver to another position when 40 the tension on the power spring weakens, and means carried by the driver and movable into position upon the release of the lock to maintain the lock in released position.

9. The combination of a retriever disk, a 50 spring constantly urging the disk in one direction of rotation, means for rotating the disk in the reverse direction and against the action of the spring, a locking device carried by the disk for normally locking the disk against rotation in either direction, means coöperating with the locking device to hold the disk, means for releasing the lock, and mechanism under the control of the spring for maintaining the 55 lock in released position during rotation of the disk by the spring, the mechanism embodying an element having engagement with the spring and normally held in one position relative to said disk by the action of the 60 spring, a control spring for moving the ele-

ment to second position when the tension of the first mentioned spring is relaxed, and a movable member carried by the element to engage and hold the lock in released position when the element is in normal position 70 and adapted by movement of the element into the second position to be carried out of engagement with the lock which will then be maintained in released position by engagement with the element.

10. The combination of a rotatable retriever disk, a spring for rotating the disk in one direction, means for rotating the disk in the opposite direction and against the action of the spring, a driver having engagement with the spring and a connection 80 with the disk whereby the disk and driver may move relatively to each other, a locking device carried by said disk and dependent upon movement of said driver to permit movement of the device into position for locking the disk against rotation by the spring, means tending to maintain the locking device in locking position, and means coacting with the device when in locking 85 position for holding the disk.

11. The combination of a rotary retrieving disk, a casing in which it rotates, a spring for rotating the disk in one direction, 90 a locking device carried by the disk adjacent to the periphery thereof, spaced stops on the casing engageable by and between which the lock is adapted to be positioned during rotation of said disk in the direction to wind up the spring, after the tension 95 on the spring has reached a predetermined value for locking the disk against rotation by the spring, and means operable after the predetermined tension of said spring has been reached to permit the lock to move into 100 locking position.

12. The combination of a rotary retriever disk, a spring tending to rotate the disk in one direction, means for rotating the disk in the other direction to wind up the spring, 110 a locking device carried by the disk and operable when set to hold the retriever disk against rotation by the spring, means to co-operate with the locking device to hold the disk, means actuated by centrifugal force 115 to engage and release the locking device to permit rotation of the disk by the spring, a driver having engagement with the spring and a yieldable connection with the disk for transmitting power of the spring to the 120 disk and for controlling the setting of the locking device, the driver operating to maintain the locking device in released position while the spring is being wound up and compelling the winding up of said spring to a 125 predetermined tension prior to the setting of the device.

13. In a device of the character described, the combination of a casing, a rotatable retrieving member therein, a spring to rotate 130

the member in one direction, a lock carried by the retrieving member operable when set to hold the member against rotation by the spring, means coöperating with the lock 5 when set to hold the retrieving member against rotation, a rotatable trolley rope reel, means interposed between the member and reel operable by centrifugal force to release the lock and to interlock the reel with 10 the member so that the reel will rotate by action of the spring upon release of the lock, means for winding up the spring, and means under the control of the spring and operable upon a predetermined tensioning of the 15 spring for controlling the setting of the lock.

14. In a device of the character described, the combination as set forth in claim 13, the last mentioned means consisting of a driver 20 connected to the spring and retrieving member and arranged for rotation relatively to the member and normally maintained in po-

sition and out of engagement with the lock by tension of the spring, said driver operating to transmit power of the spring to the 25 disk and movable into engagement with the lock during unwinding of the spring to prevent setting of the lock prior to the winding up of the spring to a predetermined tension. 30

15. In a trolley retriever the combination of a case, a retrieving disk mounted herein for rotation, a spring constantly tending to rotate the disk in one direction, a lock carried by the disk and operable when set to hold the disk against rotation by the spring, means under the control of the spring and operable upon a predetermined tensioning of the spring for controlling the setting of the lock, and means engageable by the lock 35 when set to hold the spring under tension. 40

In testimony whereof I affix my signature.

SAMUEL S. MATTHES.
